UNITED STATES PATENT OFFICE

153,191

DESIGN FOR A HASSOCK OR THE LIKE

Wilson H. Walters, Omaha, Nebr., assignor to Frontier Products Company, Inc., a corporation of Nebraska

Application April 11, 1947, Serial No. 138,305

Term of patent 3½ years

(Cl. D15—8)

To all whom it may concern:

Be it known that I, Wilson H. Walters, a citizen of the United States, residing at Omaha, in the county of Douglas, State of Nebraska, have invented a new, original, and ornamental Design for a Hassock or the like, of which the following is a specification, reference being had to the accompanying drawings, forming part thereof.

Fig. 1 is a perspective view of a Hassock or the like, showing my new design.

Fig. 2 is a plan view of a hassock or the like, and,

Fig. 3 is a corner elevational view thereof.

I claim:

The ornamental design for a hassock or the like, as shown.

WILSON H. WALTERS.
